CORDED TAPE

James A. Hendley, Middletown, Conn., assignor
to The Russell Manufacturing Company, Middletown, Conn., a corporation of Connecticut

Application February 1, 1944, Serial No. 520,634

11 Claims. (Cl. 139—384)

1

This invention relates to improvements in corded fabric which is adapted to be made as a tape having a corded edge for mounting slide-fasteners or the like thereon.

One object of this invention is to provide an improved corded fabric which is adapted to be made as a tape for mounting slide-fasteners or the like thereon, in which the cord is woven in with the body of the tape at the time of manufacture of the tape.

Another object of this invention is to provide an improved corded fabric which is adapted to be made as a tape for the mounting of slide-fasteners thereon, in which the tape is characterized by superior strength and flexibility.

With the above and other objects in view, as will appear to those skilled in the art from the present disclosure, this invention includes all features in the said disclosure which are novel over the prior art.

In the description and claims, the various parts and steps are identified by specific terms for convenience, but they are intended to be as generic in their application as the prior art will permit.

In the accompanying drawing forming part of the present disclosure, in which certain ways of carrying out the invention are shown for illustrative purposes:

Fig. 1 is a front elevation or face view of a piece of corded tape made in accordance with the present invention, and illustrated as having slide-fastener elements mounted thereon;

Fig. 2 is a schematic enlarged view similar to Fig. 1 of the area 2 of Fig. 1;

Fig. 3 is a transverse sectional view taken on line 3—3 of Fig. 2;

Fig. 4 is a longitudinal sectional view taken on line 4—4 of Fig. 3;

Fig. 5 is a view similar to Fig. 3 of a modified construction;

Fig. 6 is a view similar to Fig. 5 of still another modified construction; and

Fig. 7 is a transverse sectional view on line 7—7 of Fig. 1.

Referring to Figs. 1 to 4 of the drawing showing the particular form of the invention chosen for illustration therein, the corded tape 10 includes a relatively-thin tape-body 11 formed of longitudinal warp strands 12 interwoven with transverse weft strands or picks 13, and includes a relatively-thick twisted cord 14 formed of a plurality of twisted cord-strands 15, 16, 17 and 18, with the weft strands 13 woven transversely between certain of the twisted cord-strands, as shown.

2

In making the particular tape 10 illustrated in Figs. 1 to 4 inclusive, the cord-strands 15, 16, 17 and 18 are given one-quarter of a complete twist for every four picks 13, although it will be appreciated that a greater or less number of picks per quarter-twist could be employed. Thus, by observing Fig. 2 of the drawing, it will be seen that four picks are illustrated as passing beneath the cord-strands 18 and 17, and the next four picks pass beneath the cord-strands 15 and 18, and so on. Four weft picks pass transversely between the four cord-strands with two cord-strands above and two below each pick. The angle of passage of the portions of the picks that 15 extend between the cord-strands, varies in successive picks of any group of four picks, in accordance with the stresses which are present as the result of the twisting of the cord-strands, as will be evident from a consideration of Figs. 3 to 4 of the drawing. The different cord-strands 15, 16, 17 and 18 are marked with different surface-indications on Figs. 2 and 4, so that the eye can readily follow the continuity of the various strands throughout their extent.

25 The two warp strands 19 and 20 to the right of the twisted cord 14, serve as anchor-strands for the weft picks or strands 13.

In the form of the invention illustrated in Fig. 5, the tape-body 11 is formed of interwoven warp strands 12 and weft strands 13, the same as for the form of the invention illustrated in Figs. 1 to 4 inclusive, but in this figure the anchor warp strand 20 is omitted so that there is only the one anchor warp strand 19 to the right of the twisted cord 14 which latter is formed of the cord-strands 15, 16, 17 and 18.

In the modified form of the invention illustrated in Fig. 6, the tape-body 11 is formed of interwoven warp strands 12 and weft strands 13, 40 the same as heretofore shown and described for the forms of the invention previously illustrated, but instead of using only four cord-strands to form the twisted cord, five strands 21, 22, 23, 24 and 25 are employed to form a twisted cord 26, 45 and the weft strands 13 are anchored without employing any anchor warp strands to the right of the cord 26, by being passed around first one, then around the next, of the successive cord-strands 21, 22, 23, 24 and 25, as the twist imparted 50 to these strands successively brings first one and then another to the position of strand 21 shown in Fig. 6.

Fig. 7 and Fig. 1 illustrate the manner in which the usual form of slide-fastener elements 27 are fastened along the corded edge of the tape.

Instead of having four picks for each quarter-twist of the cord-strands, there could be more picks or less picks per quarter-twist if desired. Instead of having the cord made of four cord-strands, it could be made of more cord-strands or less cord-strand, but it is preferable to have an even number of cord-strands in the forms of the invention illustrated in Figs. 1 to 5 inclusive, in order to have an equal number of cord-strands on the opposite sides of the picks passing through the cord. For similar reasons, it is preferable to employ an odd number of cord-strands in the form of the invention illustrated in Fig. 6. For simplicity of illustration, the tape-body has been shown in the drawing as made of a simple basket weave, but it will be appreciated that any desired form of weave can be employed.

Corded tape made according to this invention has greater strength and flexibility than corded tape as heretofore made by sewing cord on previously woven tape. Also the cord will not pull off of my improved tape. Also my improved tape can be made more cheaply, and as it is made complete before dyeing, there are no color- or shade-matching troubles.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

I claim:

1. A corded tape for slide-fasteners and the like, including: a relatively-thin tape-body having interwoven longitudinal warp strands and transverse weft strands; and a relatively-thick cord extending longitudinally adjacent one edge of said tape-body and having a plurality of longitudinal twisted cord-strands with at least some of said weft strands extending transversely through approximately the middle of said cord with a plurality of the cord-strands on each side of said transversely-extending weft strands, and each of said cord-strands extending helically of said cord substantially throughout the length of said cord.

2. A corded tape for slide-fasteners and the like, including: a relatively-thin tape-body having interwoven longitudinal warp strands and transverse weft strands; and a relatively-thick cord extending longitudinally adjacent one edge of said tape-body and having a plurality of longitudinal twisted cord-strands with at least some of said weft strands extending transversely between certain of said twisted cord-strands and anchored adjacent the outer edge of said cord by being interwoven with a longitudinal strand adjacent said outer edge of said cord with a plurality of the cord-strands on each side of said transversely-extending weft strands, and each of said cord-strands extending helically of said cord substantially throughout the length of said cord.

3. A corded tape for slide fasteners and the like, including: a relatively-thin tape-body having interwoven longitudinal warp strands and transverse weft strands; a relatively-thick cord extending longitudinally adjacent one edge of said tape-body and having a plurality of longitudinal twisted cord-strands; one or more longitudinal anchor warp strands extending longitudinally adjacent the outer edge of said cord; and at least some of said weft strands extending

transversely between certain of said twisted cord-strands and anchored by being interwoven with said one or more anchor warp strands, and each of said cord-strands extending helically of said cord substantially throughout the length of said cord.

4. A corded tape for slide fasteners and the like, including: a relatively-thin tape-body having interwoven longitudinal warp strands and transverse weft strands; a relatively thick cord extending longitudinally adjacent one edge of said tape-body and having a plurality of longitudinal twisted cord-strands; one or more longitudinal anchor warp strands extending longitudinally adjacent the outer edge of said cord; and at least some of said weft strands extending transversely through approximately the middle of said cord between certain of said twisted cord-strands and anchored by being interwoven with said one or more anchor warp strands with a plurality of the cord-strands on each side of said transversely-extending weft strands, and each of said cord-strands extending helically of said cord substantially throughout the length of said cord.

5. A corded fabric including: a relatively-thin fabric-body having interwoven longitudinal warp-strands and transverse weft-strands; and a relatively-thick cord extending longitudinally adjacent one edge of said fabric-body and having a plurality of longitudinal twisted cord-strands with at least some of said weft-strands extending transversely between certain of said twisted cord-strands and anchored adjacent the outer edge of said cord by being interwoven with a longitudinal strand adjacent said outer edge of said cord, and each of said cord-strands extending helically of said cord substantially throughout the length of said cord.

6. A corded fabric including: a relatively-thin fabric-body having interwoven longitudinal warp-strands and transverse weft-strands; and a relatively-thick cord extending longitudinally adjacent one edge of said fabric-body and having a plurality of longitudinal twisted cord-strands with at least some of said weft-strands extending transversely between certain of said twisted cord-strands and anchored adjacent the outer edge of said cord by being interwoven with a longitudinal strand adjacent said outer edge of said cord with a plurality of the cord-strands on each side of said transversely extending weft-strands, and each of said cord-strands extending helically of said cord substantially throughout the length of said cord.

7. A corded fabric including: a relatively-thin fabric-body having interwoven longitudinal warp-strands and transverse weft-strands; and a relatively-thick cord extending longitudinally adjacent one edge of said fabric-body and having a plurality of longitudinal twisted cord-strands with at least some of said weft-strands extending transversely between certain of said twisted cord-strands and anchored adjacent the outer edge of said cord by being interwoven with a longitudinal strand adjacent said outer edge of said cord with an equal number of cord-strands on each side of said transversely extending weft-strands, and each of said cord-strands extending helically of said cord substantially throughout the length of said cord.

8. A corded fabric including: a relatively-thin fabric-body having interwoven longitudinal warp-strands and transverse weft-strands; and a relatively-thick cord extending longitudinally

adjacent one edge of said fabric-body and having a plurality of longitudinal twisted cord-strands with at least some of said weft-strands extending transversely between certain of said twisted cord-strands and anchored adjacent the outer edge of said cord by being interwoven with a longitudinal cord-strand adjacent said outer edge of said cord, and each of said cord-strands extending helically of said cord substantially throughout the length of said cord.

9. A corded fabric including: a relatively-thin fabric-body having interwoven longitudinal warp-strands and transverse weft-strands; and a relatively-thick cord extending longitudinally adjacent one edge of said fabric-body and having a plurality of longitudinal twisted cord-strands with at least some of said weft-strands extending transversely between certain of said twisted cord-strands and anchored adjacent the outer edge of said cord by being interwoven with a longitudinal cord-strand adjacent said outer edge of said cord with a plurality of cord-strands on each side of said transversely extending weft-strands, and each of said cord-strands extending helically of said cord substantially throughout the length of said cord.

10. A corded fabric including: a relatively-thin fabric-body having interwoven longitudinal warp-strands and transverse weft-strands; and

a relatively-thick cord extending longitudinally adjacent one edge of said fabric-body and having a plurality of longitudinal twisted cord-strands; one or more longitudinal anchor warp-strands extending longitudinally adjacent the outer edge of said cord; and at least some of said weft-strands extending transversely between certain of said twisted cord-strands and anchored by being interwoven with said one or more anchor warp-strands, and each of said cord-strands extending helically of said cord substantially throughout the length of said cord.

11. A corded fabric including: a relatively-thin fabric-body having interwoven longitudinal warp-strands and transverse weft-strands; and a relatively-thick cord extending longitudinally adjacent one edge of said fabric-body and having a plurality of longitudinal twisted cord-strands; one or more longitudinal anchor warp-strands extending longitudinally adjacent the outer edge of said cord; and at least some of said weft-strands extending transversely through approximately the middle of said cord between certain of said twisted cord-strands and anchored by being interwoven with said one or more anchor warp-strands, and each of said cord-strands extending helically of said cord substantially throughout the length of said cord.

JAMES A. HENDLEY.
